US00D985014S

(12) **United States Design Patent** (10) Patent No.: **US D985,014 S**
(45) Date of Patent: ** May 2, 2023

(54) **DISPLAY SCREEN OR PORTION THEREOF WITH GRAPHICAL USER INTERFACE**

(71) Applicant: **FURUNO ELECTRIC CO., LTD.**, Hyogo (JP)

(72) Inventors: **Naohiro Kanamaru**, Nishinomiya (JP); **Kohji Nishiyama**, Nishinomiya (JP); **Kentaroh Hamamoto**, Osaka (JP)

(73) Assignee: **FURUNO ELECTRIC CO., LTD.**, Hyogo (JP)

(**) Term: **15 Years**

(21) Appl. No.: **29/805,091**

(22) Filed: **Aug. 25, 2021**

(30) **Foreign Application Priority Data**

Feb. 26, 2021 (JP) ..... 2021-003985 D

(51) **LOC (14) Cl.** **14-04**

(52) **U.S. Cl.**

USPC **D14/486**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outermost dot-dash broken lines illustrate a display screen or portion thereof and form no part of the claimed design.

1 Claim, 1 Drawing Sheet
